(57) **CLAIM**

The ornamental design for golf putter, as shown and described.

DESCRIPTION

The patent or application file contains at least one drawing executed in color. Copies of this patent or patent application publication with color drawing(s) will be provided by the Office upon request and payment of the necessary fee.

Figure 1.1 is a first left side elevational view of a golf putter showing my new design;

Figure 1.2 is a second left side elevational view thereof;

Figure 1.3 is an enlarged left side elevational view thereof;

Figure 1.4 is a left side view thereof, showing the golf putter in an angled position;

Figure 1.5 is a right side view thereof, showing the golf putter in an angled position;

Figure 1.6 is a front elevational view thereof;

Figure 1.7 is an enlarged front elevational view thereof;

Figure 1.8 is a top plan view thereof;

Figure 1.9 is a bottom plan view thereof;

Figure 1.10 is a top front left perspective view thereof; and

Figure 1.11 is an enlarged top front left perspective view thereof.

The blue sections in the drawings illustrate the portions of the golf putter that form no part of the claimed design.
